United States Patent Office

Des. 181,512

Patented Nov. 19, 1957

181,512

COMBINED BATHTUB AND TOILET BOWL

Francis J. Zupon, Detroit, Mich.

Application February 23, 1956, Serial No. 40,282

Term of patent 3½ years

(Cl. D4—4)

FIG. 1.

FIG. 2.

Fig. 1 is a perspective view of a combined bathtub and toilet bowl showing my new design.

Fig. 2 is a top plan view of the same.

The appearance of the undisclosed side and front of the toilet bowl and tub is substantially plain and smooth.

I claim:

The ornamental design for a combined bathtub and toilet bowl, as shown and described.
